US0D1085949S

(12) **United States Design Patent** (10) **Patent No.:** **US D1,085,949 S**
(45) **Date of Patent:** **** Jul. 29, 2025**

(54) **MOTORCYCLE**

(71) Applicant: **Burromax LLC**, Kirkwood, MO (US)

(72) Inventor: **Kenneth Francis**, Kirkwood, MO (US)

(73) Assignee: **Burromax LLC**, Kirkwood, MO (US)

(**) Term: **15 Years**

(21) Appl. No.: **29/897,738**

(22) Filed: **Jul. 18, 2023**

(51) LOC (15) Cl. **12-11**

(52) U.S. Cl.

USPC **D12/110**

(58) **Field of Classification Search**

USPC D12/107, 110, 111, 117; D21/432, 538

CPC B62K 11/00; B62K 11/02; B62K 11/04;

B62K 11/10; B62K 17/00; B62K 19/00;

B62K 22/02/00

(57) **CLAIM**

The ornamental design for a motorcycle, as shown and described.

DESCRIPTION

FIG. 1 is a front and left side perspective view of a motorcycle, showing my new design;

FIG. 2 is a rear and left side perspective view of the motorcycle shown in FIG. 1;

FIG. 3 is a front and right side perspective view of the motorcycle shown in FIG. 1;

FIG. 4 is a rear and right side perspective view of the motorcycle shown in FIG. 1;

FIG. 5 is a left side elevation view of the motorcycle shown in FIG. 1;

FIG. 6 is a right side elevation view of the motorcycle shown in FIG. 1;

FIG. 7 is a front elevation view of the motorcycle shown in FIG. 1;

FIG. 8 is a rear elevation view of the motorcycle shown in FIG. 1;

FIG. 9 is a top plan view of the motorcycle shown in FIG. 1; and,

FIG. 10 is a bottom plan view of the motorcycle shown in FIG. 1.

The broken lines in the drawing depict portions of the motorcycle that form no part of the claimed design.

1 Claim, 10 Drawing Sheets
